PERMUTATION LOCK

Sampson D. Foster, Cordova, Tenn., assignor of one-third to Clarence A. Carson, one-sixth to Frank R. Wright, and one-sixth to Guy I. Frazier, all of Memphis, Tenn.

Application June 9, 1943, Serial No. 490,145

3 Claims. (Cl. 70—309)

This invention relates to permutation locks, and is here shown as applied to the steering post, as of an automobile, for locking it against turning and is of essentially the same general type as that shown in Patent No. 1,316,946.

In that patent, a permutation lock was described which was adapted, as here, to lock the steering post of an automobile. As there shown, the locking bolt when moved into locking position does not disturb the combination and unless turned may be withdrawn and the lock released without the necessity of working the combination, thus leaving it, if such turning be neglected, open to theft in much the same manner as any ordinary lock would be were the key not removed.

It also is often desirable that change be made in the combination, at least in part, as when a car equipped with a lock has been purchased from a prior user, who, unless such change were made, would be able, without further, to work the combination and remove the car illegally.

The objects of the invention are:

To provide a locking device of the above character in which the unlocking movement of withdrawing the bolt and subsequent relocking movement, upset the combination preventing subsequent release until resetting of the combination is made.

An additional object of the invention is to provide blocking means for the device which may be disengaged and shifted when the device is unlocked to provide change in at least one element of the combination.

A further object is to provide a device of the character described that is simple in construction, efficient in operation, and one that can be manufactured and placed on the market at a minimum cost.

A still further object is to provide a device of the character described in which movement of the locking bolt may be used to close an electric circuit, as the ignition circuit of an automobile.

The means by which these and other objects, as well as the nature, characteristic features and scope of the invention, will be further disclosed hereinafter in the specification, and these and other objects will readily be understood upon reference to the accompanying drawing, in which

Fig. 1 is a sectional elevation taken on the longitudinal center line of the locking bolt.

Fig. 2 is a fragmentary elevation showing the knob and related indicia by which the combination may be set.

Figs. 3 to 7 inclusive, are transverse sections taken respectively on the lines III—III, IV—IV, V—V, VI—VI, and VII—VII, of Fig. 1, all looking in the same direction, as shown by the arrows thereon.

Fig. 8 is a similar section taken, as in Fig. 7, on the line VII—VII, but with the blocking lug shifted to blocking position; and

Fig. 9 is a fragmentary sketch showing an alternate barrel construction detail.

Referring now to the drawing in which the various parts are indicated by numerals:

11 is a rotatably mounted steering post, usual in automobiles or other vehicles, and 13 the usual tubular casing surrounding the post. Disposed around the casing 13 is a two part bracket 15—16, which interlocks around the post. After engagement around the post, the two parts are relatively secured by driving a pin 17 preferably flush with the exterior surface of the head, this pin, if desired, extending into securing engagement with the casing 13.

The casing 13 and the bracket part 15—16 may be apertured in alignment to receive a bushing 19 which prevents shift or turning of the head with regard to the casing.

Secured in the bracket part 16, as by a pin 21, driven flush with the surface of the head, is a cylindrical barrel 23 which is concentric with the bushing 19 and is closed at its outer end by a head 25 which may be integral with the sleeve, or, as shown in Fig. 9, be secured therein, as by a pin or pins 27. The head 25 and bushing 19 are bored concentric with the barrel 23 to slidably and rotatably mount a locking bolt 29, which is of length to project beyond the bushing and into locking engagement with the steering post, which is suitably apertured to receive it.

Oppositely the bolt extends beyond the head 25 and has secured on its projecting end a knob 31 by which it may be turned and also longitudinally shifted. The knob may be secured to the bolt by a pin 33 which snugly fits, but which may be easily driven out to remove the knob and obtain access to the barrel head for making shift of the bushing blocking locking device, as will be later indicated. The barrel 23 also extends beyond the head 25 and houses a substantial part of the knob 31 and covers the pin 33 when the bolt 29 is in locked position.

The knob, where exposed beyond the barrel, in locked position of the bolt, is provided with indicia markings, as marked and designated by the numerals "0" and "10," in Fig. 2, there preferably being thirty of these markings equally

spaced around the knob. 35 is a cooperating marking or indicia indicator on the barrel 23.

Bolt 29 intermediate its length is successively provided with a locked-position groove 37, a latch release lug 39, an unlocked-position groove 41, and tumbler lugs 43, 45, 47 and 49. In manufacture, lug 39 is positioned about 140 degrees from lug 43 to establish a maximum movement in unblocking and the other lugs individually shifted with relation to lug 43, in usual manner, by the 12 degree increments required by the thirty knob markings, to establish the variation in permutation combinations desired.

Disposed within the casing is a blocking structure through which the bolt 29 passes, this structure comprising a cylindrical base 51 and a cylindrical cap 53, the base resting on the head 25 and being prevented from turning relatively thereto by a set screw 55, which engages any selected one of a plurality of conical indentations 57 in the base, the number of indentations corresponding to the number of indicia markings, and the top of the cap closely underlying the lug 43. The base 51 is radially bored to receive a ball 59 and spring 61 by which the ball is held in engagement with the groove 37 when the bolt is in locked, and with the groove 41 when in unlocked, position, and is provided with a longitudinal groove 63, Figs. 7 and 8, to allow outward shift of unlatching lug 39 from locked to unlocked position. The base is also cut away to receive a latch arm 65, leaving a more or less arcuate sector 67 to support the cap 53, the sector being spaced from the bolt 29 to clear the lug 39.

The latch arm 65 is hingedly mounted on a pin 69 and extends arcuately about halfway around the bolt 29, and is urged toward the bolt by a spring 71. At its free end the arm carries a blocking stop 73, which extends to the level of the top of the cap 53. Cap 53 has a radial notch 75 to permit unlocking movement of the lug 43 therethrough. This notch has a lateral extension 77 which houses the stop 73 clear of the notch 75 when the lug 43 is shifted to unlocking position.

Arm 65 is also provided with an inwardly extending cam portion 79 which is adapted for engagement by the lug 39, on turning movement of the bolt 29 in either direction, to shift the arm 65 laterally against opposition to the spring 71.

81 is an ear of greater width than the slot 75 and pin 43, which may be carried by a resilient arm 83 suitably secured in a channelway cut in the inner face of the sector 67, which ear engages the arm 65 to hold it in such laterally shifted position when shift by lug 39 has been accomplished (Fig. 7), and until the ear is subsequently depressed by outward movement of the lug 43. When the ear is so depressed the arm 65 (Fig. 6), moves against the lug 43 and overlies part of the ear 81, holding it depressed until subsequent movement of lug 39 moves the arm outward to position shown in Fig. 7, and releases it.

Disposed against the cap 53 is a short sleeve 85 which is annularly shouldered at its inner end to rotatably receive a tumbler disc 87, this disc, as shown in Fig. 5, having a radial slot 89 through which the lug 45 may outwardly pass 70 when the slot is shifted to proper position. From opposite sides of the notch 89, pins 91 extend outwardly laterally from the disc to form a guideway maintaining the lug 45 in slot alignment during its outward movement. The pins 75

91 also serve, one or the other as the case may be, to be engaged by the lug 43 when the bolt is rotated.

Overlying the disc 87 and resting on the upper end of the sleeve 85, so that binding of the disc 87 against rotation does not occur, is a second sleeve 93, similar to the sleeve 85, which similarly supports a second tumbler disc 95. This disc also is provided with a slot 97 and outwardly extending guideway pins 99 adapted to be engaged by the lug 45, and with an inwardly extending pin 101 spaced some ninety degrees from the slot.

103 is a third sleeve, supporting a third tumbler disc 105, having a slot 107, and guide pins 109 which are adapted for engagement by the pin 101. 111 is a sleeve confining disc 105.

All of the discs are provided with bores, as the bore 113 of disc 87, of such size that they cannot contact the bolt 29 and be displaced by turning movement thereof, and are so mounted in the sleeves that they turn with extreme ease. Also the tumbler lugs 43, 45, 47, and 49 are so disposed that with the bolt held in locking position by the ball 59 and cooperating groove 37 they barely clear the faces of their respective tumbler discs, and any attempt to "feel" the slots in the grooves results in displacement of the discs.

If it be desired to use the device to effect making and breaking of an electric circuit, the sleeve 19 may be made of insulating material, as hard rubber or the like, and a metallic ring 115 be imbedded therein. In such case a limited section 117 of the bolt 29 is made of reduced diameter so that contact with the ring 115 is avoided when the bolt 29 is in locked position. When in unlocking and the bolt is drawn outward the head of the bolt makes contact with the ring 115.

119 is an insulated wire leading from the ring, and 121 the second circuit wire, here shown as establishing a ground, as is usual in automobile and other vehicle brackets.

It will be understood that the switch may be used in connection with the locking feature of the bolt or that either the locking feature or the switch may be independently used, as may be desired, and that while the bracket 15, 16 is shown as attaching the lock to the steering post of an automobile, the bracket may be adapted for securing in some other place entirely divorced from the steering post, or even from a vehicle.

In operation, assuming that the device is in locked position, as shown in Fig. 1, the knob 31 is turned in usual manner, twice to the right, until a first indicia number of the combination on the knob aligns with the indicator 35. During this movement the lug 43 engages one of the pins 91 carried by the disc 87, turning that disc, the lug 45 engages one of the pins 99, and the pin 101 engages one of the pins 103, shifting the tumbler disc 105 to desired position. The knob is then reversely turned, picking up the other of the pins 91 on the disc 87 and one of the pins 99 on the disc 95 and is turned to bring the second combination indicia on the knob into alignment with the indicator 35, and the disc 95 into proper alignment. The knob is then again turned to the right, the lug 43 engaging the first engaged pin 91 and shift continued until the third combination indicia registers with the indicator and the knob is finally shifted again to the left, alining the fourth combination indicia with the indicator; and the lug 43 over the slot 75 in the cap of the blocking device.

In the first turning movement of the knob 31, above described, the lug 39 engages the cam 79 on the arm 65 shifting that arm outward in sufficient amount to allow the ear 81 to be moved upward by the resilient member 83 into latching engagement with the end of the arm 65 and during subsequent turning movements to hold that arm in such outwardly shifted position. This outward movement moves the stop 73 clear of the slot 15 and opens that slot to receive the lug 43, and the bolt 29 may be pulled outward releasing locking action of the bolt on the steering post 11 or closing the circuit through the lead wire 119 and grounded bolt 29, in well known manner.

In outward movement of the plunger the ball 59 is displaced from the groove 37, the lug 39 moves downward into the groove 63 and eventually the ball 59 engages the groove 41, holding the bolt against other than intentional displacement. Also the lug 43 in its downward movement engages the ear 81, depressing that ear below the arm 65, allowing the spring 71 to shift the arm into the position shown in Fig. 6, with the stop 73 against the lug 43 and the arm overlying the ear 81 and holding same down during subsequent movement.

In the movement of the various lugs 45, 47 and 49, the pins 91, 99 and 109 respectively prevent any accidental shifting movement of the discs 87, 95 and 105 which might otherwise prevent opposite locking movement.

To lock the device the knob 31 is pushed inward, the various lugs 43, 45, 47 and 49 again moving to their position as initially shown. However, the lug 43 slides upward along the stop 73, which, having been released by depression of the ear 81, now bears against the lug 43 until that lug clears the upper end of the stop and permits shift of the stop into the position shown in Fig. 8, closing the slot 75 against any attempted unlocking of the device until the lug 39 may have been turned substantially 180 degrees and the combination in general upset.

I claim:

1. A permutation lock including a barrel, heads closing the inner and outer ends of said barrel, a bolt rotatably journaled in said heads and slidably shiftable from locked to unlocked position and vice versa, said bolt extending beyond said outer head, a knob on the extending end of said bolt for turning and shifting said bolt, a plurality of annular tumbler discs disposed in said barrel and each having a slot therethrough, sleeves arranged in said barrel journaled said discs for free turning movement and spacing said discs relatively to each other and said head, said bolt having lugs for engaging and turning said discs selectively to position said slots, and adapted to pass through said positioned slots in unlocking movement of said bolt, including a lug for accomplishing turning movement only of said discs, and an additional unblocking lug; and means, cooperating with said turning lug to prevent unlocking movement of said bolt, said means including a base member supported by said outer head, a cap member supported by said base member in spaced relation thereto, and adapted to overlie said unblocking lug when said bolt is in locked position, said cap member having a first slot adapted to permit unlocking movement of said turning lug and a lateral slot leading therefrom, said members being apertured for said bolt, an arm disposed between said members and pivotally hinged at one end to at least one thereof, resilient

means urging said arm toward said bolt, said arm having at its opposite end and in said slot a stop extending substantially flush with the inner face of said cap and shiftable into said lateral slot, and a cam portion engageable momentarily by turning movement of said unblocking lug, an ear disposed below said first slot, and of size to underlie an adjacent portion of said lateral slot, resilient means urging said ear into said slots in latching relation to said arm when said arm is laterally shifted by said unblocking lug, said ear being compressible by unlocking shift of said turning lug into said first slot, said unblocking lug being of length to engage said cam only of said arm and shift said arm and stop clear of said ear by turning movement of said bolt and releasing said arm and stop against said turning lug in overlying relation to said ear on further turning movement of said bolt.

2. A permutation lock including a barrel, heads closing the opposite ends of said barrel, a bolt rotatably journaled in said heads and slidably shiftable from locked to unlocked position and vice versa, said bolt extending beyond one said head, a knob on the extending end of said bolt for turning and shifting said bolt, a plurality of annular tumbler discs disposed in said barrel and each having a slot therethrough, sleeves arranged in said barrel journaled said discs for free turning movement and spacing said discs relatively to each other and said head, said bolt having lugs for engaging and turning said discs selectively to position said slots, and adapted to pass through said positioned slots in unlocking movement of said bolt, including a lug for accomplishing turning movement only of said discs, and an additional unblocking lug; and means, cooperating with said turning lug to prevent unlocking movement of said bolt, said means comprising a structure slotted to permit movement of said turning lug, from locked to unlocked position, stop means resiliently urged into said slot to prevent movement, means forming part of said stop means and cooperating with said unblocking lug on turning movement of said bolt for displacing said stop means from said slot, means for latching said stop means in displaced position, said latching means being compressible into unlatching position by unlocking movement of said turning lug into said slot, to release said stop means against said turning lug, said latching means being adapted for engagement and holding in such depressed position by said stop means when said means is released against said turning lug.

3. A permutation lock including a barrel, heads closing the opposite ends of said barrel, a bolt rotatably journaled in said heads and slidably shiftable from locked to unlocked position and vice versa, said bolt extending beyond one said head, a knob on the extending end of said bolt for turning and shifting said bolt, a plurality of tumbler discs disposed in said barrel and each having a slot therethrough, sleeves arranged in said barrel journaled said discs for free turning movement and spacing said discs relatively to each other and said head, said discs having bores for the passage of said bolt, said bolt having lugs for engaging and turning said discs selectively to position said slots, and adapted to pass through said positioned slots in unlocking movement of said bolt, including a lug for accomplishing turning movement only of said discs, and an additional unblocking lug; means,

cooperating with said turning lug to prevent unlatching movement of said bolt, said means comprising a structure slotted to permit movement of said turning lug, from locked to unlocked position, stop means resiliently urged into said slot to prevent movement, means forming part of said stop means and cooperating with said unblocking lug on turning movement of said bolt for displacing said stop means from said slot, means for latching said stop means in displaced position, said latching means being depressible

5 into unlatching position by unlocking movement of said turning lug into said slot, to release said stop means against said turning lug, said latching means being adapted for engagement and holding in such depressed position by said stop means when said means is released against said turning lug; and resiliently urged means co-operating with said bolt for displaceably positioning said bolt respectively in locked and unlocked position.

SAMPSON D. FOSTER.
